(57) **CLAIM**

The design for a renewable energy production and charging station, as shown and described.

DESCRIPTION

FIG. 1 is a perspective view of a renewable energy production and charging station in accordance with a first embodiment of the design of the present invention.

FIG. 2 is a front view thereof.

FIG. 3 is back view thereof.

FIG. 4 is left side view thereof.

FIG. 5 is a right side view thereof; and,

FIG. 6 is a top view thereof.

Broken lines in the figures are for illustrative purposes only and form no part of the claimed design. Specifically, dashed lines define unclaimed features of the claimed design.
